ELECTRIC HEATER

Filed Dec. 31, 1923

INVENTOR
WALTER CLARK

William S. Fowler
ATTORNEY

UNITED STATES PATENT OFFICE.

WALTER CLARK, OF TORONTO, ONTARIO, CANADA.

ELECTRIC HEATER.

Application filed December 31, 1923. Serial No. 683,733.

To all whom it may concern:

Be it known that I, WALTER CLARK, a citizen of Dominion of Canada, and resident of Toronto, in the county of York and 5 Province of Ontario, Dominion of Canada, have invented certain new and useful Improvements in Electric Heaters, of which the following is a specification.

This invention has relation to certain 10 new and useful improvements in electric heaters of the portable type and has for its primary object the provision of a simplified and improved construction with novel heating elements suspended on the heating 15 element supporting and heat reflecting plate of the heater.

The invention has for another object the provision of an electric heater of the character stated in which is employed an articulate plate for supporting the heating elements and reflecting the heat rays both downwardly and upwardly as well as forwardly.

The invention has for another object the 25 provision of an electric heater of the character stated which is composed of the minimum number of parts of simple construction and arrangement and which may be readily assembled or taken apart, as occasion 30 requires.

With the foregoing and other objects in view as will appear as the description proceeds, the invention consists in the novel construction, combination and arrangement 35 of co-operating elements as hereinafter more specifically set forth, claimed and shown in the accompanying drawings forming a part of the present application, in which:—

Fig. 1 is a front elevation of the improved heater.

Fig. 2 is a transverse vertical section, substantially on the plane of line 2—2 of Fig. 1, looking in the direction indicated by the arrows.

Fig. 3 is a slightly enlarged fragmentary detail section, substantially on the plane of line 3—3 of Fig. 2, looking in the direction indicated by the arrows.

Fig. 4 is a fragmentary detail section, 50 substantially on the plane of line 4—4 of Fig. 1, looking in the direction indicated by the arrows.

Fig. 5 is an enlarged fragmentary detail section, substantially on the plane of line 55 5—5 of Fig. 3, looking in the direction indicated by the arrows.

Referring more in detail to the drawings in which similar reference characters designate corresponding parts throughout the several views, it will be noted that the heater includes substantially C-shape end plates 10 with depending corner legs 11, as shown clearly in Fig. 2. The end plates 10 may be gray iron castings, if preferred and are placed in parallel spaced relation with the steel body plate 12 mounted therebetween. The steel body plate 12 is also of substantially C-shape in cross section or end elevation and the longitudinal edges thereof are engaged in slots 13 provided 60 therefor in the inner faces of the end plate 10. The upper and lower edges of the body plate 12 are curved upon themselves to form the rounded upper and lower forward edges 14 for the body plate 12, as shown clearly 65 in Figs. 1 and 2. The front plate 15 is spaced forwardly of the main portion of the body plate 12 with its longitudinal edges engaged in slots 16 provided therefor in the inner faces of the end plates 10 and substantially parallel with the main portion of the slots 13 for the longitudinal edges of the body plate 12. This will be clear from 70 Figs. 2 and 4 of the drawings. It will also be noted from these views that the main or 75 central portions of the body plate 12 and the front plate 15 are substantially vertical, while the upper and lower portions are curved with the upper and lower longitudinal edges 17 of the front plate 15 engaged 80 against the turned back upper and lower longitudinal edges of the body plate 12. The front plate 15 is preferably a polished 85 copper plate and serves as a heating element supporting plate and a heat reflecting 90 and spreading plate. Connecting and bracing rods 18 are extended through the upper and lower portions of the end plates 10 to connect the same and retain the body plate 12 and front plate 15 in proper position between the end plates 10. This is clearly 95 shown in Figs. 1 and 2.

Projecting forwardly through the central or vertical portion of the front plate 15 are upper and lower binding posts 19 100 which are insulated from the front plate 15 by mica washers 20 or other suitable means. A porcelain bushing 21 is positioned in the body plate 12 near the lower portion thereof and current conducting wires 22 are extended through the porcelain bushing 21 and connected with the first 105 110

and last lower binding posts 19, as shown in Figs. 2 and 3. Hollow porcelain tubes 23 are suspended between the corresponding upper and lower binding posts 19 and are 5 supported in position by the turns or coils 24 of the heating element or wire 25. By referring to Figs. 1, 2, 3 and 5 it will be seen that a single heating element or wire 25 is employed and arranged with its ends 10 connected with the lower corner binding posts 19. The wire or heating element 25 has its coils wound around the porcelain tubes 23 with the upper and lower turns of each coil extended through suitable openings 15 near the upper and lower ends of the porcelain tubes 23. The wire or heating element 25 is extended across the binding posts 19 to connect the same in pairs between the porcelain tubes 23, first at the 20 upper ends of the latter and then at the lower ends thereof, as shown clearly in Fig. 3.

Positioned in front of the wire or heating element 25 and the porcelain tubes 23 25 is a grating which includes upstanding bars 27 mounted across horizontal or longitudinal bars 28, which latter have their ends 29 bent back and then offset outwardly to form fingers 30 engaged in recesses 31 in the end plates 10. This is clearly shown in Figs. 1, 2 and 4 and it will be evident from these 30 views that the grating will serve to protect the porcelain tubes 23 and the element or wire 25, as well as the binding posts 19. Furthermore, the grating will prevent placing 35 of the heater too close to furniture or any other article. It is also apparent that the front plate 15 will serve to reflect the heat rays from the element or wire 25 upwardly and downwardly as well as outwardly and at the same time serve as a firm support for binding posts 19 on which the heating element or wire 25 is suspended 40 with the porcelain tubes 23.

The body plate 12 has an air opening 45 32 in its lowermost portion and a handle 33 mounted on its uppermost portion and insulated therefrom by suitable insulating washers 34 carried on the fastening members 35 employed for attaching the ends of the handle 33 to the top of the body plate 12. Therefore, the handle 33 may be employed for lifting and carrying the heater when the same is in use, without danger of burning the hand engaged with the handle 33.

It is believed the complete construction and operation of the heater may now be 50 apparent from the foregoing paragraphs taken in connection with the accompanying drawings without further detail description. It may be briefly stated, however, that the heater may be employed whenever desired and the wires 22 connected with 55 service wires or distributing wires, by

means of a plug or the like. Owing to the shape of the end plates 10, the body plate 12 and the front plate 15, the heat rays will be reflected in such a manner as to assure the highest efficiency of operation 70 at the minimum expense.

While the preferred embodiment of the invention has been disclosed it is to be understood that minor changes in the details of construction, combination and arrangement of co-operating elements may be resorted to within the scope of what is claimed without departing from the spirit of the invention.

What I claim as new is;

1. A heater of the character stated, including a body substantially C-shaped in vertical cross section formed of spaced plates; ends for said body; a heating element mounted forwardly of said body; and 85 a guard disposed forwardly of said heating element.

2. A heater of the character stated, including a body substantially C-shaped in vertical cross section formed of spaced 90 plates; plates mounted on the ends of said body serving to constrain said plates in spaced relation; a heating element mounted forwardly of said body; and a guard 95 disposed forwardly of said heating element.

3. An electric heater including end plates; a curved body plate secured between said end plates; a correspondingly curved front plate secured between said end plates and parallel with the main portion of the body plate; a heating element mounted on the front of said front plate and spaced therefrom; a guard supported by said end plates in front of said heating element; and connecting members extended through said end plates between the body plate and front plate.

4. An electric heater including end plates having their upper and lower portions curved; a curved body plate supported between said end plates with the edges of said body plate engaged in said end plates; a front plate supported in a similar manner between said end plates and parallel with the main portion of said body plate; heating means mounted on the central portion of said front plate; said heating means including a heating element having up-standing coil portions carried on porcelain tubes and connected above and below said porcelain tubes with binding posts in pairs; a guard carried by said end plates and extended in front of the heating means; current conducting wires extended through said body plate and insulated therefrom; said current conducting wires being connected with the first and last binding posts; said body plate having an air opening in its lower portion; a handle carried by and insulated from the upper portion of said body 120 125 130

plate; and connecting rods extending through said end plates between the body plate and the front plate.

5. An electric heater including end plates of substantially C-shape and having depending corner legs; a body plate of substantially C-shape extended between said end plates and having its longitudinal edges secured therein; the upper and lower edges of said body plate being curved back upon themselves to form rounded upper and lower edges for the body of the heater; a front plate having curved upper and lower portions and extended between said end plates with the longitudinal edges of said front plate secured in the end plates; said front plate being substantially parallel with the main portion of the body plate; the central portions of said body plate and

said front plate being vertical; heating means mounted on the central portion of the front plate and including a coiled wire spaced outwardly of the central portion of said front plate; a guard mounted between said end plates and extending forwardly of the heating means; the body plate and the front plate serving to form an air compartment therebetween; said body plate having an air opening in its lower portion; a handle mounted on and insulated from the upper portion of said body plate; and connecting rods extending through said end plates between the body plate and the front plate.

In testimony whereof, I affix my signature.

WALTER CLARK.
